UNITED STATES PATENT OFFICE.

LEVI M. BOWMAN, OF TULSA, OKLAHOMA, ASSIGNOR OF ONE-EIGHTH TO FINIS W. HENDERSON, OF TULSA, OKLAHOMA.

LIGHT-MODIFYING MEANS FOR HEADLIGHTS.

Application filed April 17, 1926. Serial No. 374,514.

To all whom it may concern:

Be it known that I, LEVI M. BOWMAN, a citizen of the United States, residing at Tulsa, county of Tulsa, and State of Oklahoma, have invented certain new and useful Improvements in Light-Modifying Means for Headlights, of which the following is a specification.

My invention relates to headlights and particularly to headlights for automobiles. More specifically my invention relates to light modifying means for headlights.

The object of my invention is to provide light modifying means for headlights wherein the obnoxious glare of the headlight is eliminated, but which will not interfere with the illumination of the roadway in advance of the car. In carrying out my invention I arrange the light modifying means either adjacent to or within the lens of the headlight, and when the latter form is used, the light modifying means constitutes means for reinforcing the lens. A further object of my invention therefore, is to provide in a headlight, light modifying means which shall also constitute lens reinforcing means. Other objects will appear hereinafter.

With these objects in view my invention consists generally in a plurality of substantially parallel, forwardly and downwardly inclined non-transparent members arranged either within the lens or adjacent the same, whereby light rays from the headlight are prevented from being projected above the horizontal but which will permit the rays to pass freely and unobstructed below substantially the horizontal. My invention further consists in a device as mentioned in which the upper and outer faces of said parallel members are non-reflecting. Preferably, the under and inner faces are reflecting surfaces. My invention further consists in a device as mentioned in which the said parallel members are connected by members extending transversely thereof. My invention further consists in a headlight lens of transparent vitreous material, in combination with a plurality of substantially parallel downwardly and outwardly inclined members molded therein. My invention further consists in various details of construction and arrangements of parts all as will be fully described hereinafter and particularly pointed out in the claim.

My invention will be more readily under-

stood by reference to the accompanying drawings forming a part of this specification and in which—

Fig. 1 is a diagrammatical, vertical longitudinal section of a headlight equipped with my improved light modifying means in its preferred form, 60

Fig. 2 is a front elevation of the same,

Fig. 3 is a detailed sectional view of the lens shown in Fig. 1 upon an enlarged scale, 65

Fig. 4 is a similar view of the modified form, and

Fig. 5 is a similar sectional view of a modified form wherein the light modifying means is arranged adjacent the lens, 70

Referring now to the drawings, 1 indicates a headlight of which 2 is the reflector and 3 the light bulb. These portions of the device, which form no part of my invention of themselves, may be of any desired or preferred form and for this reason they are illustrated diagrammatically only.

4 indicates the lens which is formed of transparent vitreous material such as glass; and in the preferred form of my invention, the light modifying means is cast within the lens when the latter is molded, as illustrated in Figs. 1 to 4 inclusive of the drawings. The light modifying means comprises a plurality of substantially parallel members 5 which are preferably arranged horizontal within the lens. These members incline downwardly and outwardly as clearly illustrated in the drawings and are so positioned that the outer lower edge of each member is substantially on a level with, or slightly below the upper inner edge of the member directly beneath the same. These members are made of non-transparent material, and by the arrangement shown and described all light rays above the horizontal are obstructed but those below the horizontal are practically unobstructed.

To avoid undesirable reflecting of the rays above the horizontal, the outer upper surfaces 6 are made non-reflecting. Preferably, the lower surfaces 7 of the members are reflecting surfaces, which increase the magnitude of the light thrown downwardly upon the roadway. The members 5 are connected by thin vertical strips 8 which hold members 5 in position while being molded within the lens and which also constitute reinforcing means for the lens.

In the form of lens illustrated in Figs. 1 110

22
to 3 the edges of the members 5 are spaced from the outer surfaces of the lens; but in Fig. 4 I have illustrated a modified form wherein the forward edges of the members 5 extend to the front face of the lens, and the faces of the portions of the lens between the said members are inclined inwardly and downwardly giving a prismatic effect.

If preferred, my light modifying means 10 may be formed separately of the lens and arranged adjacent its inner faces as illustrated in Fig. 5. By this arrangement the light rays are arrested and deflected before reaching the lens, but the effect will be substantially the same.

A suitable material from which to form the light modifying means whether molded within the lens or formed independently thereof, is thin strips of white metal. When

this is used, the upper outer surfaces of the 20 upper outer surfaces may be blackened or dulled to produce the desired result.

I claim:

A lens, in combination with a light ray 25 directing shutter molded therein, said shutter comprising a plurality of substantially parallel, outwardly and downwardly inclined reflecting plates and strips extending transversely to the plates and connecting the same, substantially as described. 30

In testimony whereof I have signed my name to this specification in the presence of two subscribing witnesses.

LEVI M. BOWMAN.
